UNITED STATES PATENT OFFICE

BEN JAMES LEVIN, OF NEW YORK, N. Y.

COMBINATION POLISHING BRUSH

Application filed March 27, 1931. Serial No. 525,661.

This invention relates to polishing brushes and pads and contemplates particularly, the provision of a combination polishing device wherein convenient means are provided for applying polish to the article to be polished, for initially brushing the polish, and for then performing the final polishing operation.

My invention further contemplates the provision of a simple and comparatively inexpensive polisher wherein the various polishing parts are accessibly assembled on a single handle in such positions that each of the polishing means may be used separately and successively and in the proper order, with a minimum expenditure of time and energy, and without danger of any of the parts being lost or misplaced.

The various objects of my invention will be clear from the description which follows, and from the drawing, in which

Fig. 1 is a perspective view of a combined polishing brush, pad, and dauber, showing the preferred form of my invention.

Fig. 2 is a vertical section of one end of the handle, and showing the means for connecting the polishing pad to the handle.

Fig. 3 is a similar view of a modified form of the connecting means wherein both ends of the pad are turned under.

Fig. 4 is a horizontal section of one form of the means for securing the polish-applying brush to the handle.

Fig. 5 is an elevational view of the polish-applying brush indicating that the bristles may be secured directly in the end of the handle, or by any other suitable means, and

Fig. 6 is a side elevation of a modified form of my improved combination polishing brush.

In that practical embodiment of my invention which I have illustrated by way of example, the handle 10 is designed and proportioned to support and maintain the various parts in easily accessible cooperative relation. Said handle is preferably made of a comparatively narrow elongated block of suitable material, such as wood, bakelite, metal or other suitable comparatively rigid supporting material. On the widened part of the upper surface 11 of the handle, is suitably secured the polishing pad 12, which is preferably made of

a length of sheepskin or other suitable and comparatively soft, fluffy, and yieldable polishing material stuffed or underlaid with a suitable layer or pad of felt or the like. On the under face 42 of the handle, which under face is preferably parallel to the upper face, the bristles 13 are suitably secured to form a polishing brush as by being set into suitable perforations 14 made in the under face of the handle in a manner which will be obvious and hence need not be described in detail. As shown in Figs. 1, 4 and 5, one end of the handle as 15 is preferably made in a double conical form. The outermost portion 16 of the end tapers inwardly toward its extremity, while the conical handle portion 17 tapers inwardly in the opposite direction, the conical parts thereby meeting along a circle 18, determining the greatest diameter of the conical portions.

Intermediate the conical end 15 and the flat and widened pad and brush-supporting portion 19 of the handle, the handle is curved or tapered as at 20 to provide a handle grip suitably shaped to fit and to be grasped by the hand of the user.

The upper and lower surfaces of the handle grip 20 may be partly flat and a continuation of the upper and lower surfaces, respectively, of the handle block 10, or said handle grip may be otherwise suitably shaped for the purpose intended. On one surface 11 of the handle block 10 is arranged the final polishing pad 12 as has been previously indicated, and which is made preferably of sheepskin having comparatively soft polishing hairs 21 exposed for use and having a leather backing part 22. Said backing may be suitably secured to the handle 10, as by means of suitable cement or the like or by other suitable fastening means such as the nails, tacks, screws or rivets 23.

It will be understood that the pad may be formed of other material than sheepskin such as cotton, fabric or the like, having the proper resiliency or fluffiness, and polishing properties. The pad is secured in place with the layer 24 of felt between the back 22 and the handle surface to properly space and cushion the polishing material from the

handle and to take up the major part of the stress put thereon. The felt 24 is secured to the back as by means of suitable fastening elements such as the nails 25 or the like 5 driven through the felt and into the upper surface 11 of the handle, or by suitable cement, if desired.

To secure the sheepskin pad 12 in place, the end 26 thereof is first turned under into 10 engagement with the upper surface 11 of the handle and preferably, under the pad 24, suitable nails or tacks as 27 being used to secure said end 26 together with the felt to the top of the handle. The length of 15 sheepskin is then drawn forwardly toward the right to cover the felt, whereafter the end 28 thereof is secured to the end 29 of the handle by means of the nails, tacks or similar fastening means 30, as shown in Fig. 20 2, or said end may first be turned under as at 45, and the fastening means 46 driven through the pad into the handle block, the end of the fastener 46 being covered by the fluffy part of the pad (Fig. 3).

25 It will be understood that wherever the nails or tacks 25, 27 and 30 are driven into the handle, said tacks are so arranged as not to interfere with the bristles 13 which form the brush 31. It will further be understood that while I prefer to arrange the pad 12 directly opposite and of substantially the same length and width as the brush 31, said pad may be otherwise arranged on the handle 10 in a manner which will be obvious 35 and hence which need not be shown or described.

Preferably at the end 15 of the handle, the dauber brush 32 is secured. As one method of securing said brush in place on 40 the conical member of the handle, the bristles 33 of said brush may be set around a suitable bristle positioning block 34. Said block is secured in position preferably by means of a suitable screw 47 passing into the handle. 45 The conical metallic ferrule 35 is spaced from the surface of the conical portion 16 and suitable cement as 48 arranged between the block 34 and the ferrule to hold the ends of the bristles in place.

50 As illustrated in Fig. 5, the block 34 and the ferrule 35 may be dispensed with, and the bristles 33 may be set directly into the conical portion 16 in the same manner as the bristles 13 are set into the flat part of the handle. It will be understood that any other means well known in the art may be used, if desired, for securing the bristles 32 and 13 in place, and that I do not wish to limit myself, therefore, except as hereinafter claimed, 55 to the precise structure whereby the bristles are secured to the handle.

As illustrated in Fig. 6, the dauber brush 32 may be arranged at the same end of the handle as are arranged the polishing elements 12 and 31. In this form of my inven-

tion, the end of the handle grip 20 is merely rounded off, while the other end 40 of the handle is extended and formed in the same shape as the conical portions 16 and 17 for the reception of the bristles forming the 70 dauber.

It will be seen that the handle 10 serves not only as a handle grip which can be conveniently and easily grasped by the hand of the user for convenient operation of my improved brush, but that the handle serves the further function of a securing means for the pad, a holding means for the brush bristles, and means for securing and supporting the bristles for convenient operation thereof. 75 The user is not compelled to change from one type of brush or polisher to another, but by grasping the handle grip can first dip the bristles into a suitable polish, applying the polish where desired as to an article of furniture, stove or shoes, as the case may be, the user then performing the second part of the polishing operation without releasing the brush, but by simply turning the brush 80 into engagement with the surface to which the polish has been applied. Then, without releasing the grip upon the handle grip 20, my improved brush need merely be turned over to bring the pad 12 into polishing position, whereby the polishing operation may 85 readily be completed in much less time than would be required, if the user were compelled to use three separate and disconnected polishing brushes.

It will be seen, furthermore, that by means 90 of my improved brush, all the parts are permanently arranged conveniently at hand, without danger of being lost or misplaced, and that the polishing operation may proceed in regular order or in any order, as may 95 be desired, the various brushes or pads being alternated as may be found necessary to properly perform the operation without releasing the brush at any time.

While I have shown and described certain 100 specific embodiment of my invention, it will be understood that I do not intend to limit myself thereto but that I intend to claim my invention as broadly as may be permitted by the state of the prior art and 110 the scope of the appended claims.

I claim:

1. A brush supporting member having a broad flat portion adapted to be arranged between and to support a pad and bristles, a 120 narrow projection extending longitudinally from said flat portion, and an enlarged terminal portion on the projection adapted to support dauber bristles and cooperating with the projection to form a handle, and adapted to have the heel of the user's hand rest thereon to position the hand on the handle.

2. In a brush, a brush handle, a broad and long flat portion adapted to be arranged between a pad and bristles to support the same, 125

a narrow projection extending longitudinally from said flat portion, curved side edges on the projection shaped to fit the hand of the user, and an enlarged integral terminal portion on the projection, said terminal portion being conical and adapted to support dauber bristles in the end thereof and co-operating with the projection to form the end part of the handle, and said terminal portion being adapted to engage the heel of the user's hand to position the hand on the handle.

BEN JAMES LEVIN.
